CLAIM

The ornamental design for a pet chew toy, as shown and described.

DESCRIPTION

FIG. 1 is a front right perspective view of a first embodiment of the pet chew toy showing our new design.

FIG. 2 is a front elevation view thereof.

FIG. 3 is a rear elevation view thereof.

FIG. 4 is a right side view thereof.

FIG. 5 is a left side view thereof.

FIG. 6 is a top plan view thereof.

FIG. 7 is a bottom plan view thereof.

FIG. 8 is a front right perspective view of a second embodiment of the pet chew toy showing our new design.

FIG. 9 is a front elevation view thereof.

FIG. 10 is a rear elevation view thereof.

FIG. 11 is a right side view thereof.

FIG. 12 is a left side view thereof.

FIG. 13 is a top plan view thereof; and,

FIG. 14 is a bottom plan view thereof.

The pet chew toy of FIGS. 8-14 is shown with a symbolic break in its length. The appearance of the pet chew toy between the broken break lines of FIGS. 8-14 forms no part of the claimed design.
